UNITED STATES PATENT OFFICE.

WALTER H. CLARKE, OF AKRON, OHIO.

DESIGN FOR A RUBBER HEEL.

53,359.

Specification for Design.

Patented May 27, 1919.

Application filed October 10, 1918. Serial No. 257,663. Term of patent 14 years.

To all whom it may concern:

Be it known that I, WALTER H. CLARKE, a citizen of the United States, residing at Akron, in the county of Summit and State of Ohio, have invented a new, original, and ornamental Design for a Rubber Heel, of which the following is a specification, reference being had to the accompanying drawings, forming a part thereof.

In said drawing, Figure 1 is a plan view

of the heel embodying my new design and Fig. 2 is a vertical section through the center of the heel.

I claim:

The design for a rubber heel substantially as shown.

WALTER H. CLARKE.

Witnesses:

A. J. HUDSON,

L. I. PORTER.
